UNITED STATES PATENT OFFICE

139,089

DESIGN FOR A CONDIMENT RECEPTACLE

Le Mar M. Peck and Frederick J. Gilbert,
Los Angeles, Calif.

Application December 24, 1943, Serial No. 112,082

Term of patent 3½ years

(Cl. D44—22)

To all whom it may concern:

Be it known that we, Le Mar M. Peck and Frederick J. Gilbert, citizens of the United States, residing at Los Angeles, in the county of Los Angeles, State of California, have invented a new, original, and ornamental Design for Condiment Receptacles, of which the following is a specification, reference being had to the accompanying drawing, forming part thereof.

Fig. 1 is a side elevational view of a condiment receptacle, showing our new design;

Fig. 2 is a substantially corresponding plan view thereof, with a part removed therefrom; and

Fig. 3 is a perspective view of said part looking up from the bottom thereof.

We claim:

The ornamental design for a condiment receptacle, as shown and described.

LE MAR M. PECK,
FREDERICK J. GILBERT.
